COMBINED SHIPPING AND PARTITIONING CONTAINER FOR CYLINDRICAL OBJECTS OR THE LIKE

Anthony R. Zine, Jr., Corning, N.Y., assignor to
Corning Glass Works, Corning, N.Y.

Filed Mar. 13, 1972, Ser. No. 334,470

Term of patent 14 years

U.S. Cl. D9—184   Int. Cl. D9—03

Fig. 1

Fig. 2

Fig. 3

Fig. 4

Fig. 5

FIG. 1 is a front elevational view of a combined shipping and partitioning container for cylindrical objects or the like embodying my new design;

FIG. 2 is a top plan view with the cover open;

FIG. 3 is an end elevational view with the cover open and the front panel in a partially open position, the opposite end being a mirror image of the end shown;

FIG. 4 is a front view with the cover open and the front panel in a full open position;

FIG. 5 is a view similar to FIG. 4 but showing a modified form of my new design; and

FIG. 6 is a developed plan view showing the relationship of the container and partitioning member.

I claim:

The ornamental design for a combined shipping and partitioning container for cylindrical objects or the like, as shown and described.
